UNITED STATES PATENT OFFICE.

EDWARD WILLIAM POPPE, OF KALAMAZOO, MICHIGAN, ASSIGNOR TO KALAMAZOO PAPER BOX COMPANY, OF KALAMAZOO, MICHIGAN, A CORPORATION OF MICHIGAN.

DISPLAY BOX.

Application filed October 31, 1921. Serial No. 511,614.

To all whom it may concern:

Be it known that I, EDWARD WILLIAM POPPE, a citizen of the United States, residing at Kalamazoo, county of Kalamazoo, State 5 of Michigan, have invented certain new and useful Improvements in Display Boxes, of which the following is a specification.

This invention relates to improvements in display boxes.

10 The main object of the invention is to provide an improved display box having a plurality of trays in which the bottom tray is automatically projected with the opening of the cover.

15 A further object is to provide a box having these advantages which is comparatively simple and economical in structure and very attractive in appearance.

20 Objects pertaining to details and economies of construction and operation will definitely appear from the detailed description to follow.

25 I accomplish the objects of my invention by the devices and means described in the following specification. The invention is clearly defined and pointed out in the claims.

30 A structure which is a preferred embodiment of my invention is clearly illustrated in the accompanying drawing forming a part of this specification, in which:

Fig. I is a perspective view of a display box embodying the features of my invention with the box closed.

35 Fig. II is a vertical longitudinal section on a line corresponding to line 2—2 of Figs. I and III.

Fig. III is a vertical transverse section on a line corresponding to line 3—3 of Figs. I and II.

40 Fig. IV is a vertical transverse section on a line corresponding to line 3—3 of Fig. I with the box open.

45 In the drawing the sectional views are taken looking in the direction of the little arrows at the ends of the section lines and similar numerals of reference refer to similar parts throughout the several views.

50 In the accompanying drawing I have shown the walls and other parts of the box conventionally and without regard to the manner of forming or building up the same, as these details form no part of my invention.

55 The body of my improved display box comprises the front wall 1, rear wall 2, end

walls 3, and bottom 4. The bottom is arranged to project at the front of the box as at 5 constituting a support for the front wall 1 which is hinged at 6 to swing or collapse to a horizontal position as shown in Fig. IV. 60

For the sake of appearance the bottom is preferably made to project on all sides of the box. The cover 7 is hinged to the rear wall 2 at 8 and is provided with flanges 9, the front flange engaging the wall 1 and supporting it in its closed position. 65

The box is provided with a horizontal partition 10 forming a plurality of tray compartments, the tray 11 resting in the upper compartment and the tray 12 being slidable 70 in the lower compartment and being supported in its projected position as shown in Fig. IV by the collapsed front wall 1, which is in turn supported by the projecting portion 5 of the bottom. 75

The bottom tray 12 is automatically projected upon the opening of the cover being operatively connected thereto by the tapes or cords 13. These are preferably formed in one piece, the ends being connected at 14 80 within the flange of the cover and roved or passed through the spaced holes 15 and 16 which are located adjacent the front of the box. The tapes or cords are also rove through holes 16' in the rear wall of the 85 bottom tray and adjacent its ends, the bight portion 17 on the inside of the tray as illustrated so that the tape is free to equalize thus avoiding great accuracy in assembling.

With the parts thus arranged, when the 90 cover is opened the pull on the cords or tapes 13 projects the bottom tray as shown in Fig. IV. When the box is closed it is necessary to push this tray back into its compartment, lifting the front wall and closing the cover over the same which holds the parts in closed position. 95

My improved box is quite economical to produce, is attractive in appearance and not likely to get out of repair in use. It is 100 especially designed as a confectionery box and the like, although adapted for other uses.

Having thus described my invention what I claim as new and desire to secure by Letters Patent is:

1. The combination of a box body comprising front, rear and end walls, a bottom projecting beyond the front wall, the front wall being hinged at its lower edge to col- 110

lapse upon and be supported by the projecting bottom, said box having a horizontal partition providing a plurality of tray compartments, a cover hinged to the rear of the 5 box body and provided with a flange engaging and supporting the front wall when the box is closed, trays, the bottom tray being 10 slideable in the bottom tray compartment, a tape secured at its ends within the cover flanges, the end walls of said box each having 15 spaced guide holes therein, one of which is located adjacent the front thereof, the rear wall of the bottom tray having holes adjacent its ends, said tape being rove through 20 said holes in said tray and end walls with the bight portion of the cord within the tray so as to equalize therein and so that when the cover is opened the front wall collapses upon the projecting bottom and the 25 bottom tray is projected over said front wall.

2. The combination of a box body comprising front, rear and end walls, a bottom projecting beyond the front wall, the front wall being hinged at its lower edge to collapse upon and be supported by the projecting bottom, said box having a horizontal partition providing a plurality of tray compartments, a cover hinged to the rear of the box body and provided with a flange engaging and supporting the front wall when the box is closed, trays, the bottom tray being 30 slideable in the bottom tray compartment, and tray operating cords connected with said cover and to the rear of the bottom tray, the 35 end walls of said box each having pairs of spaced guide holes, one hole of each pair being located adjacent the front edge of the end walls, the cords being passed through said holes so that when the cover is opened the front wall collapses upon the projecting bottom and the bottom tray is projected over said front wall.

3. The combination of a box body comprising front, rear and end walls, a bottom projecting beyond the front wall, the front wall being hinged at its lower edge to col-

lapse upon and be supported by the projecting bottom, said box having a horizontal partition providing a plurality of tray compartments, a cover hinged to the rear of the 50 body and provided with a flange engaging and supporting the front wall when the box is closed, trays, the bottom tray being slideable in the bottom tray compartment, and tray operating cords connected with said 55 cover and to the rear of the bottom tray the end walls of said box having guide holes through which the cords are passed so that when the cover is opened the front wall collapses upon the projecting bottom and the 60 bottom tray is projected over said front wall.

4. The combination of a box body comprising a front wall hinged at its lower edge, said body having a plurality of superimposed tray compartments, a cover hinged to the rear of the body and provided with means engaging and supporting the front wall when the box is closed, trays, the bottom tray being slideable in the bottom tray compartment, and a tape secured at its ends to 65 the cover, the ends of the box body having guide holes located adjacent the front of the box and through which the tape is passed, the rear wall of the bottom tray having holes therein through which the tape is passed, all 70 coacting for the purpose specified.

5. The combination of a box body comprising a front wall hinged at its lower edge, said body having a plurality of superimposed tray compartments, a cover hinged 75 to the rear of the body and provided with means engaging and supporting the front wall when the box is closed, and tray operating cords connected with the cover and to the rear of the bottom tray, the ends of the 80 box body having guide holes adjacent the front of the box through which the cords are passed, all coacting as specified.

In witness whereof, I have hereunto set my hand and seal.

EDWARD WILLIAM POPPE. [L.S.]
